UNITED STATES PATENT OFFICE.

JOHN A. HOLM, OF ALBANY, NEW YORK, ASSIGNOR TO BLUBLAZE MOTOR SPECIALTIES CORP., OF LONG ISLAND CITY, NEW YORK, A CORPORATION OF NEW YORK.

TIMER.

Specification of Letters Patent. Patented Aug. 29, 1922.

1,427,594.

Application filed December 10, 1918. Serial No. 266,142.

To all whom it may concern:

Be it known that I, JOHN A. HOLM, a citizen of the United States, and resident of Albany, county of Albany, State of New York, have invented an Improvement in Timers, of which the following description, in connection with the accompanying drawings, is a specification, like characters on the drawings representing like parts in each of the several views.

This invention relates to timers such as employed to control the ignition in multiple cylinder internal combustion engines and while having other and more general fields of usefulness is well adapted and designed for use in the ignition system of the well known Ford type of automobile. One principal object of the invention is to provide an improved timer construction wherein more certain and reliable contact and hence a better ignition is obtained by reason of the fact that the contacts are so disposed and arranged that they are not apt to become fouled by oil or like lubricant, the present timer being in fact adapted to operate perfectly and to best advantage without any lubricant whatever within. Further, in accordance with my invention the contacting surfaces are laterally arranged, i. e., in a plane transverse of the timer shaft instead of peripherally as has heretofore been usual and hence a more even and smooth movement of the brush member with respect to the stationary contacts is obtained so that the wear on the contacting parts is evenly distributed and the objection which has hitherto arisen from uneven motion and cutting into the surface of the raceway is eliminated, the present timer being hence also much more quiet and steady in operation than previous types. A further object is to provide an improved arrangement of the terminal connections whereby these may be connected to the wiring all on the top of the timer so as to be more readily accessible and also free from fouling by oil dripping thereon, the present arrangement also being such that the binding posts or terminals on the top of the timer are connected to the successive stationary contacts so as to be in regular order, thus simplifying the connecting up thereof by the wiring. A further object is to provide improved means whereby the adjustment of the timer housing to advance or retard the spark does not disarrange the

wiring leading thereto. The foregoing and other objects and advantages of the invention will more fully appear from the following detailed description, and the distinctive features of novelty will be pointed out in the appended claim.

Referring to the drawings:

Fig. 1 is an inner end view of a timer constructed in accordance with my invention, the timer shaft being shown in section; 65

Fig. 2 is a lengthwise vertical section thereof, the movable contact and its mounting being shown in elevation;

Fig. 3 is a transverse section on line 3—3 of Fig. 2; 70

Fig. 4 is a detail section on line 4—4 of Fig. 1;

Fig. 5 is a detail elevation of the movable contact carrier arm removed; and

Fig. 6 is a detail elevation of a sleeve fitting within said carrier arm. 75

The present timer housing or shell 10 is of a form generally similar to, and externally substantially identical with that of the present standard Ford timer, having the usual perforated lug 10^a to receive the connection for angularly shifting said shell to advance or retard the spark and with the usual outer socket head 10^b against which the spring presser member (not shown) acts to hold 85 the timer shell against its seat. Within this metallic shell in accordance with my invention I fit and mount an annulus 11 of hard fiber or other like insulating material adapted to provide seats for the fixed contacts. 90 This annulus preferably has the outer portion of its rear face beveled as indicated at 12 to fit with a correspondingly formed seat at the base of the shell, while between the inner end portion of said annulus and the 95 shell I fit a fiber or like insulating washer 13, the purpose of forming such washer as a separate member being to permit convenient mounting of, and access to the circuit connections now to be described. In accordance 100 with my invention the fixed contacts are mounted in this fiber annulus so as to present their operative surfaces in a plane transverse of the timer shaft. For this purpose the annulus is rebated from its inner side to form 105 a transverse or vertical wall 14 and quadrantly spaced sockets are formed in the annulus extending inward from such wall to provide mountings for the fixed contact pins or blocks 15, 16, 17, 18. The upper two 110

15, 16 of these contact blocks have screwed directly thereinto the binding post terminals 19, these terminals passing through a fiber or like insulating bushing 20 set into the shell. The outer ends of these binding posts are, in accordance with my invention, provided with ball heads 19^a on which are movably fitted sockets 21 having pivot connections 22 extending therefrom to which 5
10 are connected arms 23 with circuit wire connections. By virtue of the pivoting permitted in the ball and socket joints 19^a—21 and at the pivots 22, the angular turning of the timer shell for the advance and retarding 15 of the spark is taken care of, so that little if any shifting or disarrangement of the wires engaged with the connections 23 results. In accordance with my invention the binding posts for the two lower contacts 17, 20 18 are mounted on the upper quadrant of the timer shell, and preferably so that the successive contacts around the timer are represented by binding posts successively arranged on the top of the timer shell. For 25 this purpose the lower contact blocks 17, 18 are set into shouldered seats 24 of the annulus with binding stems 25 extending therefrom which are engaged by wire or strip connections 26. The wire or strip connections 26 extend in arcuate recesses 27 at the back of the annulus upward and past the respective upper contacts 15, 16 to be clamped to blocks 28 set into the annulus but not extending to the surface of the 30 wall 14, as seen in Fig. 4. These blocks 28 have threaded thereinto binding posts 29, 30 respectively which are mounted similarly to the binding posts 19 and likewise have ball heads 31 similar to the heads 19^a and 35 40 likewise engaged with sockets and pivot connections 21, 22, 23 as already described. The recesses 27 preferably open at the back of the annulus 11 and are closed by the insulating washer 13 which is fitted to the 45 back thereof. The carrier arm 32 of the rotary contact has slidably fitted therein a contact button 33 which is pressed against the fixed contacts by a leaf spring 34 secured at its inner end to said arm and having its 50 outer end forked and slipped over a reduced neck of said button as indicated at 35. This contact button is preferably of steel while the fixed contact blocks may be of bronze or like metal. The arm 32 is formed with a 55 sleeve 36 which fits over a collar 37 adapted to be fitted on the end of the timer shaft 38. The collar 37 has a flange 37^a at one end thereof formed with a series of radial notches into a selective one of which is 60 65 adapted to engage a finger or prong 36^a on the sleeve 36 whereby the arm 32 may be

adjusted with reference to the collar 37 so as to bring the movable contact into correct operative relation with the fixed contacts. The sleeve 36 is preferably split and engaged 65 by a clamp screw 39 for clamping the same rigidly to the collar 37. For holding the collar 37 on the shaft 38 a cotter pin 40 extending through a radial slot at the end of the shaft 38 engages in registering slots 70 in the end of said collar and is held from displacement by a washer 41 which is of somewhat greater diameter than the length of said cotter pin and is formed with a seat into which said pin fits, so that the ends of 75 the pin engage the peripheral edge portion of said washer and the pin is thus provided from endwise sliding. The washer 41 is retained in place on the end of the shaft by a clamp nut 42 as usual. 80

The timer of the present invention dispenses with any requirement for internal lubrication, the need for which has caused the fouling of the contacts in previous timers of this type. The described arrangement of the contacts, and terminals, with the connections from the two lower fixed contacts brought up past the adjacent upper contact to binding posts at the top of the timer shell, not only makes the wiring connections more convenient and accessible, and not apt to be fouled by lubricant, but permits the disposition of the successive contacts one after another in a line at the top of the timer housing so that proper connection with 90 their respective wires is insured without any particular care or attention to this end. I am aware that the invention may be embodied in other specific forms without departing from the spirit or essential attributes thereof, and I therefore desire the present embodiment to be considered in all respects as illustrative and not restrictive, reference being had to the appended claim rather than to the foregoing description to 95 indicate the scope of the invention. 100

Having described my invention, what I claim as new and desire to secure by Letters Patent is:

An ignition timer comprising a housing, 110 an insulating annulus fitted therein, a plurality of spaced fixed contacts mounted in said annulus, a shaft extending into said housing, a collar fixed on the end of said shaft and having a flange at one end formed 115 with a series of radial notches, an arm carrying a movable contact and provided with a sleeve fitting over said collar and having a finger to engage said notches in the collar.

In testimony whereof, I have signed my 120 name to this specification.

JOHN A. HOLM.
